(57) **CLAIM**

The ornamental design for a lid for beverage container, as shown and described.

DESCRIPTION

FIG. 1 is a top front left perspective view of a lid for beverage container, showing my new design;

FIG. 2 is a front view of the lid for beverage container illustrated in FIG. 1;

FIG. 3 is a rear view of the lid for beverage container illustrated in FIG. 1;

FIG. 4 is a right-hand side of the lid for beverage container illustrated in FIG. 1;

FIG. 5 is left-hand side of the lid for beverage container illustrated in FIG. 1;

FIG. 6 is a top view of the lid for beverage container illustrated in FIG. 1; and,

FIG. 7 is a bottom view of the lid for beverage container illustrated in FIG. 1.

The broken lines in the drawings depict environmental subject matter and form no part of the claimed design.

1 Claim, 7 Drawing Sheets
